(57) **CLAIM**

(21) Appl. No.: **29/262,627**

The ornamental design for an internal reflector for remote ballast, as shown and described.

(22) Filed: **Jul. 10, 2006**

DESCRIPTION

(51) **LOC (8) Cl.** **26-99**

FIG. 1 is a perspective view of the internal reflector for a remote ballast, according to the new and unique ornamental design;

(52) **U.S. Cl.** **D26/118**

FIG. 2 is a left side view of the internal reflector for a remote ballast, according to the new and unique ornamental design, the right side being a mirror image thereof;

(58) **Field of Classification Search** D26/3,

FIG. 3 is a front side view of the internal reflector for a remote ballast, according to the new and unique ornamental design, the back side being a reversed mirror image thereof;

D26/24, 42, 72, 75, 85, 113, 118, 119, 128,

FIG. 4 is a top view of the internal reflector for a remote ballast, according to the new and unique ornamental design as shown in FIG. 1; and,

D26/120; 362/219, 257, 260, 294, 317, 362,

FIG. 5 is a bottom view of the internal reflector for a remote ballast, according to the new and unique ornamental design as shown in FIG. 1.

362/368, 217
